SLUG CASTING MACHINE

Chauncey H. Griffith, New York, N. Y., assignor to
Mergenthaler Linotype Company, a corporation
of New York

Application June 28, 1939, Serial No. 281,513

17 Claims.

(Cl. 199—47)

This invention relates to slug casting machines of the general organization represented in United States Letters Patent to O. Mergenthaler No. 436,532, wherein a composed line of matrices is presented before the front face of a slotted mold, the mouthpiece of a metal pot presented against the rear face of the mold, and molten metal injected from the metal pot through the mouthpiece into the mold slot or cavity and up against the composed line of matrices to produce a type bar or slug.

In these machines, the molds (usually four in number) are mounted on a rotatable disk, which is adjustable to bring any selected mold into use. During a machine cycle of operation, the disk is rotated periodically, first, through a quarter rotation to carry the active mold into casting position, and then after the slug has been cast, through a three-quarter rotation to bring the mold back to the slug ejecting station. During the latter rotation, the cast slug is subjected to the action of a fixed knife arranged to trim the backs or bottom edges of the slugs so that they will stand at the proper type height when subsequently assembled in a printing form.

Each mold comprises as usual a body portion, a cap portion, and a pair of intermediate liners, these latter being readily interchangeable with other liners to vary the dimensions of the slot according to the size or length of the slug to be cast. In casting slugs of the larger sizes (14 pt. or above), the cap portion of the mold is ordinarily formed with fore-and-aft core members to produce slugs of the so-called skeleton type, i. e. slugs having an overhanging character bearing portion supported by vertical ribs cast on one side of the body portion. In practice, it has been found that when slugs of this sort solidify in the mold, the supporting ribs shrink inwardly from the rear face of the mold, the distance varying with the size of the slug. In consequence, although the slugs are subjected to the action of the back trimming knife, the height of the supporting ribs in many cases is substantially less than the height of the body portion, or in other words of less than type height, and as a result the slugs tend to tilt or cant when they are assembled in a printing form.

In accordance with the present invention, means are provided for producing skeleton slugs wherein the height of the supporting ribs for the character bearing portion will always be the same as the height of the body portion of the slug, or in other words of proper type height.

To this end, specifically, the face of the mouthpiece is provided with one or more horizontal grooves so located that when the mouthpiece is presented against the rear face of the mold they extend across the fore-and-aft formed grooves between the core members of the cap portion. By this arrangement, when the slug is cast, lugs which project beyond the rear face of the mold are formed on the feet or bottom edges of the supporting ribs, these lugs being high enough to leave the supporting ribs of greater than type height even after whatever shrinkage may take place. Thereafter, as the mold disk rotates to carry the mold from the slug casting to the slug ejecting station, the lugs or excrescences thus formed on the supporting ribs are trimmed down to the same height as the body portion or to proper type height.

For a more complete description of the invention, reference may be made to the accompanying drawing. In this drawing, however, the invention has been shown merely in preferred form and by way of example, but obviously many changes and variations may be made therein and in its mode of application, which will still be comprised within its spirit. It should, therefore, be understood that the invention is not limited to any specific form or embodiment, except insofar as such limitations are specified in the claims.

Referring to the drawing:

Fig. 1 is a side view of a portion of a slug casting machine, showing in section the mold, pot mouthpiece and composed line in casting relation, the mold disk being broken away to expose the back trimming knife;

Fig. 2 is a perspective view of a slug cast and trimmed in accordance with the present invention;

Figs. 3 and 4 illustrate the difference between the old and the new type of slug, Fig. 3 being an end view of an old type of slug, and Fig. 4 being an end view of the new type of slug;

Fig. 5 is a front elevation of the mold and mouthpiece illustrated in Fig. 1, the mold being broken away to more clearly illustrate the form and arrangement of parts; and

Fig. 6 is a sectional view of the metal pot mouthpiece detached, the view being taken along line 6—6 of Fig. 5.

In the operation of these machines, a composed line of matrices 10 after composition is transferred into a so-called first elevator or line transporter 11 which immediately descends to position the line before the face of a slotted mold

12 mounted on a rotatable disk 13, the latter having been given a quarter rotation to carry the mold into casting position. The mold disk is then advanced to bring the front face of the mold into contact with the composed line of matrices, and a metal pot 22 is thereafter rocked forwardly about its pivotal axis to press the mouthpiece 14 thereof against the rear face of the mold 12 and so establish a metal tight lock-up between the parts. When the parts are thus locked-up, molten metal is injected by a pump (not shown) from the metal pot 22 through the mouthpiece 14, into the mold slot or cavity 15 and against the composed line 10 to form a type bar or slug whose characters correspond with the intaglio characters of the matrices. After the slug has been cast, the metal pot and the mold disk 13 recede and the mold disk 13 is given a three-quarter rotation to carry the mold 12 to the ejecting station, where the slug is forced out of the mold through a pair of trimming knives (not shown). During this latter operation, the slug is subject to the action of a fixed knife 16 secured to the mold slide 17 and arranged to trim the back or bottom edges of the slugs to insure that the slugs will stand at proper type height when they are subsequently assembled in a printing form.

In the embodiment of the invention illustrated, the active mold is of the sort ordinarily employed for casting slugs of the head letter or display variety (14 pt. or above), and it comprises a body portion 17 which defines one side face of the slug as cast, a cap portion 18 which defines the opposite side face of the slug as cast, and a pair of intermediate liners 19 which define the opposite end walls of the slug as cast, these liners being selected according to the size of the slug to be cast. As usual in such cases, the cap portion 18 is provided with a plurality of fore-and-aft core members 21 which are spaced from the body portion 17 and terminate short of the front face of the mold.

The mouthpiece 14 is secured to the metal pot 22 by screws 23 so that it can be replaced, and as usual it is provided with a plurality of horizontally aligned holes 24, through which the molten metal is forced into the mold cavity 15, and with a plurality of interposed vertical grooves or vents 25 of limited length to provide for the escape of air from the mold cavity 15 as the molten metal is injected. As is well known, the holes 24 are so located in the mouthpiece 14 that the molten metal is forced into the mold 12 slightly above the casting face of the mold body 17 or into the space formed between said body and the core members 21, since this part of the mold cavity is open to the inflow of molten metal throughout the entire length of the mold regardless of the size of the slug to be cast. As the molten metal is forced into the mold, it flushes upwardly and then solidifies to form a slug having a character bearing portion 27, a body portion 26, and vertical supporting ribs 28. As before stated, as the slug solidifies, the supporting ribs 28 shrink inwardly from the rear face of the mold, due, it is believed, to the absorption of heat therefrom by the slower cooling body and character bearing portions 26, 27 and thus fail to stand at full type height, somewhat as indicated in Fig. 3. In consequence, although the slugs are subjected to the action of the trimming knife 16 in the manner heretofore explained, the height of the supporting ribs 28 instead of being uniform and

equal to the height of the body portion 26 after the slugs are ejected from the mold decreases gradually from one side of the slug to the other with the result that the slugs tend to tilt or cant when assembled and locked in a printing form.

According to the present invention, this difficulty is obviated by providing the mouthpiece 14 with a plurality of horizontal grooves 29 equal in length to the length of the longest mold cavity (say, 30 ems) and arranged in superposed relationship above the usual vents 25. The grooves 29 are so located and spaced that, when the lock-up is completed, one or another of them will be positioned immediately below the level of the casting face of the cap portion 18 when the mold cavity 15 is adjusted to cast a skeleton slug of a standard point size. For example, in the embodiment illustrated, the front face of the mouthpiece 14 is provided with three grooves, the lowermost groove being so located that it will be positioned immediately below the level of the casting face of the cap portion 18 when an 18 pt. slug is to be cast, the intermediate groove being located so that it will be similarly positioned when a 24 pt. slug is to be cast, and the uppermost groove being so located that it will be thus positioned when a 36 pt. slug is to be cast. In the last-mentioned instance, of course, and as shown in the drawing, all three grooves will be effective. The grooves 29 are blind to the direct passage of molten metal from the mouthpiece 14 but those which are positioned below the level of the casting face of the cap portion 18 when the lock-up is completed will extend across the rear of the grooves between the fore-and-aft core members 21 and so become filled with molten metal during the slug casting operation. Due, however, to the elevated temperatures at which the mouthpiece 14 is maintained and to the slight amount of metal contained in the grooves 29, the metal in those portions of the grooves behind the core sections 21 does not solidify and is removed therefrom by the usual mouthpiece wiper (not shown) as the mouthpiece 14 moves rearwardly after the casting operation. The metal in those portions of the grooves 29 between the core sections 21, on the other hand, does solidify and forms lugs 32 on the bottom edges of the supporting ribs 28, this being due to the absorption of heat therefrom by the rest of the slug. The depth of the grooves 29 (although actually quite small) is made great enough to compensate for whatever shrinkage takes place during the metal congealing period or such that the lugs 32 after shrinkage will extend beyond the rear face of the mold, which determines the base trim line of the final slug. After casting and as the mold disk 13 rotates to carry the mold 12 and the cast slug to the ejecting station, the lugs 32 are trimmed down by the knife 16 to the same height as the body portion 26 or to proper type height. In consequence, when the slugs so cast and trimmed are subsequently assembled in a printing form, their bottom edges are perfectly square (see Fig. 4) and they cannot tilt or cant in the objectionable manner of the old type of slug shown in Fig. 3.

In the present embodiment of the invention, the grooves 29 are shown as being all of the same depth, since such an arrangement produces satisfactory results and presents a simple problem of manufacture. If desired, however, the depth of the grooves may be varied to correspond with the gradual reduction in the height of the supporting ribs 28 due to shrinkage and so that

the lugs 32 cast on the ribs will all project exactly the same distance beyond the rear face of the mold 12 after the casting and before the trimming operation. Moreover, instead of being continuous as herein shown, the grooves 29 might be made of discontinuous form such, for example, as to provide separate sets of lug forming recesses, one set for each rib forming groove in the mold cap. Indeed, for a mold of a given length, two sets of lug forming recesses would suffice, one for each of the rightmost and leftmost rib forming grooves. These and other modifications of the invention will be obvious to those skilled in the art.

Having thus described my invention, what I claim is:

1. In a slug casting machine, the combination of a slotted mold of the kind adapted to cast a ribbed slug, and a metal pot having a mouthpiece to contact the rear face of the mold, said mouthpiece being formed in its mold contacting face with a nonventing recess to produce on the ribbed portion of the slug lugs which project beyond the rear face of the mold.

2. In a slug casting machine, the combination of a slotted mold having a cap portion formed with depending core members separated by fore-and-aft grooves to cast a ribbed slug, and a metal pot having a mouthpiece formed with a horizontal row of metal discharge holes opening into the mold cavity in the space below the core members, said mouthpiece being formed in its mold contacting face with a horizontal groove located above the metal discharge holes in position to extend across the rear ends of the grooves which separate the core members so as to produce on the ribbed portion of the slug lugs which extend beyond the rear face of the mold.

3. In a slug casting machine, the combination of a slotted mold having a cap portion formed with depending core members separated by fore-and-aft grooves to cast a ribbed slug, and a metal pot having a mouthpiece formed with a horizontal row of metal discharge holes opening into the mold cavity in the space below the core members, said mouthpiece being formed in its mold contacting face with a plurality of superposed horizontal grooves located above the metal discharge holes in position to extend across the rear ends of the grooves which separate the core members so as to produce on the ribbed portion of the slug lugs which extend beyond the rear face of the mold.

4. In a slug casting machine, the combination of a slotted mold of the kind adapted to cast a ribbed slug, said mold being movable from casting to ejecting position, a metal pot having a mouthpiece to contact the rear face of the mold, said mouthpiece being formed in its mold contacting face with a recess to produce on the ribbed portion of the slug lugs which project beyond the rear face of the mold, and means for trimming the projecting lugs flush with the rear face of the mold as the latter moves from casting to ejecting position.

5. In a slug casting machine, the combination of a slotted mold of the kind adapted to cast a ribbed slug, said mold being mounted on a rotatable disk which carries the mold from casting to ejecting position, a metal pot having a mouthpiece to contact the rear face of the mold, said mouthpiece being formed in its mold contacting face with a recess to produce on the ribbed portion of the slug lugs which project beyond the rear face of the mold, and a rela-

tively fixed knife past which the slug is carried as the mold is moved from casting to ejecting position, said knife acting to trim the projecting lugs flush with the rear face of the mold.

6. The method of producing a ribbed type bar or slug of true type height, which consists in casting the slug with ribs of greater height than its body portion and thereafter trimming the base of the slug to bring it to proper type height.

7. The method of producing a ribbed type bar or slug of true type height, which consists in casting the slug with ribs of greater height than its body portion and thereafter trimming the base of the slug to bring the ribs flush with the body portion.

8. A type bar or slug of the ribbed variety, wherein the bottom edges of the ribs are trimmed flush with the bottom edge of the body portion to prevent canting or tilting of the slug when assembled in a printing form.

9. A type bar or slug of the ribbed variety, wherein the ribs are formed at their bottom edges with depending lugs trimmed flush with the bottom edge of the body portion to prevent canting or tilting of the slug when assembled in a printing form.

10. In or for a slug casting machine, a metal pot mouthpiece having a metal discharge passage and formed in its mold contacting face with a horizontally disposed groove distinct from said metal discharge passage and arranged to open directly into the mold cavity but otherwise closed to the atmosphere during casting, as and for the purpose described.

11. In or for a slug casting machine, a metal pot mouthpiece having a metal discharge passage and formed in its mold contacting face with a plurality of superposed horizontally disposed grooves distinct from said metal discharge passage and arranged to open directly into the mold cavity but otherwise closed to the atmosphere during casting, as and for the purpose described.

12. In or for a slug casting machine, a metal pot mouthpiece having a metal discharge passage and formed in its mold contacting face with a plurality of superposed horizontally disposed grooves distinct from said metal discharge passage, said grooves being so positioned that one or another of them will be located immediately below the level of the casting face of the cap portion of the mold and thus open directly into the mold cavity when a slug of standard point size is to be cast.

13. In or for a slug casting machine, a metal pot mouthpiece having a metal discharge passage and formed in its mold contacting face with a horizontally disposed groove distinct from said metal discharge passage and of a length equal to that of the longest mold cavity with which it is to be used and arranged to open directly into said cavity.

14. In or for a slug casting machine, a metal pot mouthpiece having a metal discharge passage and formed in its mold contacting face with a plurality of superposed horizontally disposed grooves distinct from said metal discharge passage and of equal depth and arranged to open directly into the mold cavity but otherwise closed to the atmosphere during casting.

15. In or for a slug casting machine, a metal pot mouthpiece having a metal discharge passage and formed in its mold contacting face with a plurality of superposed horizontally disposed grooves distinct from said metal discharge passage and of equal depth and of a length equal to

that of the longest mold cavity with which it is to be used and arranged to open directly into said cavity.

16. In or for a slug casting machine, a metal pot mouthpiece of the kind having metal discharge holes arranged in horizontal alignment and vertical air vents disposed between adjacent holes, said mouthpiece being formed in its mold contacting face with a horizontal groove distinct from the metal discharge holes and located above the level of the air vents but having no direct communication therewith in the mouthpiece.

17. In or for a slug casting machine, a metal pot mouthpiece of the kind having metal discharge holes arranged in horizontal alignment and vertical air vents disposed between adjacent holes, said mouthpiece being formed in its mold contacting face with a plurality of superposed horizontally disposed grooves distinct from the metal discharge holes and located above the level of the air vents but having no direct communication therewith in the mouthpiece.

CHAUNCEY H. GRIFFITH.
